Pierre James

ATTORNEY

UNITED STATES PATENT OFFICE.

WILLIAM O. KUHN, OF SEATTLE, WASHINGTON.

ROTARY INTERNAL-COMBUSTION ENGINE.

1,273,380.

Specification of Letters Patent. Patented July 23, 1918.

Application filed May 14, 1917. Serial No. 168,339.

To all whom it may concern:

Be it known that I, WILLIAM O. KUHN, a citizen of the United States, residing at Seattle, in the county of King and State of Washington, have invented certain new and useful Improvements in Rotary Internal-Combustion Engines, of which the following is a specification.

This invention relates to internal combustion engines of the rotary type, and while 10 peculiarly adapted for explosive engines, features of the invention may advantageously be utilized in steam engines.

The object of my invention is to provide 15 an engine of this class which will be of simple and economical construction and which will be efficient in operation.

The invention consists in the novel construction, arrangement and combination of 20 parts, as will be hereinafter described and claimed.

In the accompanying drawings, Figure 1 is a side elevation of an engine embodying the present invention.

Fig. 2 is a similar view with one of the 25 casing members removed and parts shown in section.

Fig. 3 is a view partly in front elevation and partly in section, said section being taken substantially through 3—3 of Figs. 1 and 2. Fig. 4 is a section through 4—4 of Fig. 2.

The reference numeral 5 designates the engine shaft journaled in bearing boxes 6 which are integrally connected by standards 35 7 with twin casing members 8, 8¹. These casing members are of annular shapes and are recessed at 9, Figs. 3 and 4, to receive the circumferential elements 10, 10¹ which constitute with the rib elements what will be 40 hereinafter designated as the rotor members. Said flange elements are formed within the casing with cylindrical outer and inner peripheral surfaces while the protruding portions are cylindrical except as to recesses A, B and C in the outer periphery and an inwardly directed protuberance D 45 from the inner periphery.

Said rib elements and the casing members are machined to mutually afford an annular chamber 12 of circular shape in transverse section.

Fixedly mounted on the shaft 5 is a wheel 13 having in its periphery a plurality of teeth 14 (Fig. 2) each of which is formed 55 with a face 15 which inclines from its root outwardly in the direction of the wheel's

rotation to the point of the tooth therein-front, so as to afford substantially triangular shaped serrations to accommodate two series of roller elements 16, 16¹ upon which 60 the aforesaid rotor members are mounted.

17 represents a spacing ring interposed between the two series of rollers to prevent any interference.

Fitting within the chamber 12 and secured to the respective rotor members, as by bolts 18, are pistons 19, 19¹.

Movable radially of the engine axis are two cylindrical plungers 20, 21 having at their respective inner ends projections 20¹, 70 21¹ which serve as stops for regulating the positions of the pistons at certain stages of their operations. The plunger 20 is provided at its outer end with ears 20², whereby it is connected through the medium of a 75 pivotal pin 22 with the arms 23 and 24 of two longitudinally arranged levers which are fulcrumed by pins 25 to lugs 26 provided on the respective casing members 8, 8¹.

The other arms 27 and 28 of said levers 80 are connected to rods 29 extending radially of the engine through spaced guides 30, 30¹ provided on said casing members, and carry at their inner ends rollers 31 which track on the flange elements 11, 11¹ of the respective rotor members. The plunger 21 is, in like manner, provided with ears 21² connected by a pin 22² with levers such as 23¹ and 24¹ to rods, as 29¹, extending through guides 30², 30³ and equipped with rollers 31¹ 90 which track on the respective flange elements 11, 11¹.

Helical springs 32 are provided between the guides 30, 30² and collars 33 of the respective rods to yieldingly retain the associated rollers 31 and 31¹ against the outer peripheral surfaces of said flange elements, and also serve when the recesses A, B and C are successively presented, to effect movements to the plungers for the purpose of 100 withdrawing the stop projections 20¹ and 21¹ thereof from the path of the pistons' travel.

34 represents a spark plug extending into the cylinder space E intermediate the two 105 pistons 19, 19¹ when occupying the positions in which they are represented in Fig. 2.

35 represents an electric contact for said spark plug and is desirably in the nature of a lever fulcrumed by pin 36 to ears 36¹ of 110 the engine casing, said contact lever having an arm 35¹ engaging in a transverse slot 37

of plunger 21 so as to be actuated by the latter when moving outwardly.

38 represents a port for the admission of an explosive mixture supplied to the cylinder through a pipe 39, and 40 is a spring for closing an inlet valve 38¹ for said port. Located in proximity to the inlet port 38 is a gate 41 movable into and from the engine cylinder 12 in radially disposed guideways 10 provided in the casing members 8, 8¹. Said gate is provided with a passage 42 which, when in the position shown in Fig. 2, communicates by a port 43 with the cylinder at the side of the gate remote from said inlet port, and has a side outlet 44 which communicates with an eduction pipe 45.

A lever 46, fulcrumed at 47 to lugs 48 provided on the casing members, connects the gate 41 with two bars 49, 49¹—one for each 20 rotor member—and having at their inner ends rollers 50 which track against the inner peripheral surface of the respective flange elements 11, 11¹. Said bars pass through guide blocks 51 secured to the casing and between such blocks and a set collar 52 of each bar is a helical spring 53 whose office is to yieldingly hold the gate in its operative position, as shown in Fig. 2.

The operation of the invention is as follows:

Assuming the pistons 19, 19¹ are in the positions in which they are represented in Fig. 2, an explosive charge ignited therebetween will serve to drive the piston 19 and 35 the rotor elements 10, 11 in the direction indicated by arrow *a*.

As the piston advances, it forces the combustion charges of the preceding explosion to escape through the gate passage. When 40 the piston 19 reaches about the position denoted by broken lines 19^a, the protuberance or cam element D of the moving rotor engages a roller 50 to swerve the associated bar 49 toward the engine axis, thereby influencing the lever 46 to withdraw the gate 41 from the cylinder 12 and thus retain the same until the piston has passed the gate, whereupon the springs 53 assert their power to effect the closing of the gate.

50 After passing the latter piston 19 compresses a charge admitted through port 38 until the compression is sufficient to overcome the inertia of the other piston 19¹, which will occur after the piston 19 has 55 passed the position in which it is indicated by broken lines 19^b.

The two pistons then advance, 19¹ being moved forward until arrested by the stop 21¹ of the plunger 21 and the other piston 60 has passed beyond the stop 20¹ of plunger 20. For such purpose, the plunger 20 is withdrawn by the associated spring 32, the movement of the related lever and rod 29 being accommodated by a recess B of the 65 respective rotor which is presented to re-

ceive the roller 31 at one side, and the roller at the other side is accommodated by the recess C of the other rotor, whose piston is arrested by the stop 21¹ of plunger 21.

After the referred-to rollers 32 have 70 passed through the respective recesses, the rollers are caused to be moved outwardly upon the outer peripheries of the rotor elements 11, 11¹ to effect the inward movement of the plunger 20 to introduce the stop 20¹ 75 thereof to the rear of the rearmost piston to prevent any retrograde movements thereof from the force due to the next explosion of the gases intermediate the pistons.

From the foregoing it is seen that the two 80 pistons act to accomplish four cycles in each revolution.

One of the pistons is held by the stop 20¹ and serves as an abutment until urged forward into the position occupied by the active piston when the fluid pressure created by the travel of the latter is capable of overcoming its inertia. The function of the stop 21¹ is to prevent the forward piston from being advanced until compression is 90 made by the other piston and the charge thus compressed is ignited.

The forward piston is then driven by the direct force of the explosion until it passes the gate 41, whereat its momentum is sufficient to accomplish the remainder of its travel and also afford the power to compress a charge.

The rotors are thus driven alternately; as each one becomes active it is coupled to the 100 wheel 13 to impart rotary motion to the shaft.

The preferred coupling devices comprising rollers 16 or 16¹ act quickly and positively with no apparent lost motion, and are 105 not only very efficient for such purpose, but also enable the wheel to rotate with respect to the idle rotor, as upon roller bearings, with a consequent little friction.

What I claim, is—

1. In an engine of the class described, a cylinder formed of two non-rotatable members and two independently rotatable members, a piston carried by each of the rotatable members within the cylinder, inlet and exhaust openings provided for said cylinder, a gate interposed between said openings, movable stops provided in the cylinder, ignition devices, a shaft, a wheel mounted thereon, and means provided to engage the wheel 115 by each of said rotors when the latter is driven in one rotary direction.

2. In an engine of the class described, a casing and two rotor members formed and combined to afford an annular cylinder, pistons provided on the respective rotor members and operable within said cylinder, radially movable stops provided in spaced relations within the casing, means coöperating with said rotor members for normally re- 120 125 130

taining said stops in operative positions within the cylinder, spring-actuated means influenced by the rotations of said rotors whereby the respective stops are withdrawn 5 from the cylinder for the progressive movements of the respective pistons, a power shaft, a wheel mounted thereon, and means interposed between said wheel and the rotors whereby they are individually coupled for 10 rotary motion.

3. In an engine of the class described, a shaft, a casing comprising two twin members and having inlet and exhaust openings, a pair of rotors having cam flange elements and peripheral rib elements extending therefrom into a space provided between said casing members, said rib elements and said casing members being formed to each contribute a fourth of the 15 peripheral wall of an annular cylinder, pistons provided in said cylinder and rigidly connected to the respective rotors, a pair of plungers mounted in the casing for reciprocatory motion radially of said shaft, stops 20 provided on the respective plungers, means actuated by said cam elements for actuating said plungers to successively introduce and withdraw the stops thereof from the cylinder, a gate operable in the cylinder between 25 30 the inlet and exhaust openings, means operable by the rotation of said rotor flange elements to effect the opening of said gate for the passage of the pistons, and operative connections between each of said rotors and the shaft to successively transmit power 35 from each of them to rotate the shaft.

4. In an engine of the class described, a casing having a fuel inlet, a pair of rotors constituting with said casing a cylinder and including pistons operable within the cylinder, a gate operable within the cylinder in proximity to the fuel inlet, means operated by said rotors for withdrawing said gate for the passage of the pistons, means to temporarily arrest the pistons in spaced relations, and means for igniting an explosive mixture between the two pistons whereby one of the latter is driven to rotate the respective rotor. 40 45

5. In an engine of the class described, a casing having a fuel inlet, a pair of rotors constituting with said casing a cylinder and including pistons operable within the cylinder, a gate operable within the cylinder in proximity to the fuel inlet, said gate being 50 provided with an exhaust passage which opens into the cylinder at its side most remote from said inlet, means operated by said rotors for withdrawing said gate for the passage of the pistons, means to temporarily arrest the pistons in spaced relations, and means for igniting an explosive mixture between the two pistons whereby one of the latter is driven to rotate the respective rotor. 55 60 65

Signed at Seattle, Washington, this 3rd day of May, 1917.
